UNITED STATES PATENT OFFICE.

HERMAN J. BUCK, OF MINNEAPOLIS, MINNESOTA, ASSIGNOR TO MATHEWS GRAVITY CARRIER COMPANY, OF ST. PAUL, MINNESOTA, A CORPORATION.

COUPLING DEVICE FOR CARRIER-SECTIONS.

1,038,842.

Specification of Letters Patent. Patented Sept. 17, 1912.

Application filed August 17, 1911. Serial No. 644,687.

To all whom it may concern:

Be it known that I, HERMAN J. BUCK, of Minneapolis, Hennepin county, Minnesota, have invented certain new and useful Improvements in Coupling Devices for Carrier-Sections, of which the following is a specification.

The object of my invention is to provide means for coupling the abutting ends of the carrier sections together which will hold them securely against relative movement and at the same time allow the convenient separation of the sections whenever desired.

A further object is to provide a carrier section coupling composed of members which shall be interchangeable and capable of application to either end of a carrier.

The invention consists generally in various constructions and combinations, all as hereinafter described and particularly pointed out in the claims.

In the accompanying drawings forming part of this specification, Figure 1 is a side elevation of the abutting ends of carrier sections, with my invention applied thereto, Fig. 2 is a similar view of one end section detached from the other one, Fig. 3 is a view, partially in section, showing the construction of one member of the coupling, Fig. 4 is a sectional view on the line $a-a$ of Fig. 2, Fig. 5 is an end view of one of the sections and of the coupling applied thereto, Fig. 6 is a detail view of one of the coupling members detached from the carrier.

In the drawing, 2 represents the abutting rails of the carrier sections wherein the rollers 3 are mounted on rods 4. The abutting ends of the rails 2 are provided with recesses 5 and yokes 6 are pivoted at 7 to the rails in the rear of said recess. These yokes comprise side bars adapted to straddle the ends of the rails and cross bars or bridges 8 and 9 between the side bars or rails. The bridge 9 projects above the side bars in position to contact with the rail at the upper edge of the recess therein and form a stop for limiting the upward swinging movement of the yoke. This bar also may rest upon the wall at the bottom of the recess, as shown in Fig. 3, and limit the downward movement of the yoke. The bar 8 has a depending extension 10, a socket 11 being formed between the bars 8 and 9 so that when the members of the coupling are brought together the de-

pending portion 10 of one coupling will 55 drop into the socket 11 in the other coupling member and lock the parts securely together as shown in Fig. 1. It will be understood that the rails are tilted out of alinement with one another to allow the coupling 60 members to be joined together and when in this position the cross bar 8 will bear on the edge of the rail at the top of its recess and the cross bar 9 will bear on the edge of the rail at the bottom of its recess, thereby preventing separation of the coupling members as long as the rails of the carrier are in alinement with one another. When the rails are tilted upwardly then the coupling members may be disengaged. 70

An important feature of this coupling device lies in the fact that the members of the couplings are interchangeable and no fitting or adjustment is required.

I do not limit myself to the details of the 75 construction herein shown and described, as it is obvious the same may be varied in many particulars without departing from my invention.

I claim as my invention:—

1. The combination, with the abutting rails provided with recessed ends, of yokes pivoted on said ends and having sockets therein and cross bars bridging said sockets, each yoke having a projection to enter 85 the socket of the other yoke, and the cross bar of one yoke bearing on the rail at the top of its recess and the cross bar of the other yoke bearing on the rail at the bottom of its recess, whereby when the rails are in 90 alinement their abutting ends will be locked together.

2. The combination, with abutting rails, of interchangeable, interlocking coupling members pivoted on said rails, each coupling 95 member having a socket to receive the other coupling member, and both coupling members having means for locking them against premature separation.

3. The combination, with rails having 100 abutting ends, of coupling members pivoted thereon, each member having a socket to receive the other member and capable of being interlocked with one another, when the rails are swung out of alinement with each other, 105 and means preventing the separation of said coupling members when the rails are in alinement with one another.

4. The combination, with rails having abutting ends, of yokes mounted thereon and having cross bars and sockets between them, the outer cross bars having depending portions adapted to enter the socket in the contiguous coupling member when the rail ends are swung out of alinement with one another, the other cross bars of said yokes engaging the edges of said rail ends and lock-

ing them together when the ends are in alinement with one another.

In witness whereof, I have hereunto set my hand this 27th day of July, 1911.

HERMAN J. BUCK.
